UNITED STATES PATENT OFFICE.

MANING F. TEN EYCK, OF CLIFTON, NEW JERSEY.

SHUTTER-FASTENER.

SPECIFICATION forming part of Letters Patent No. 477,973, dated June 28, 1892.

Application filed January 9, 1892. Serial No. 417,545. (No model.)

To all whom it may concern:

Be it known that I, MANING F. TEN EYCK, a citizen of the United States, residing at Clifton, in the county of Passaic and State of New Jersey, have invented a new and useful Shutter-Fastener, of which the following is a specification.

The invention relates to improvements in shutter-fasteners.

10 The object of the present invention is to provide a simple and inexpensive shutter-fastener and means for conveniently releasing the shutter when it is desired to close the same.

The invention consists in the construction 15 and novel combination and arrangement of parts hereinafter fully described, illustrated in the accompanying drawings, and pointed out in the claim hereto appended.

In the drawings, Figure 1 is a perspective 20 view of a portion of a window provided with a shutter-fastener constructed in accordance with this invention, the shutter being partially open. Fig. 2 is a vertical sectional view, the shutter being open. Fig. 3 is a detail perspective view of the latch.

Like numerals of reference indicate corresponding parts in all the figures of the drawings.

1 designates a gravity latch or fastener comprising a horizontal bar 2, which is provided 30 at each end with a beveled hook and a slide 3, which is vertically disposed and is arranged in a groove 4 of a window-shutter 5^a. The slide is adapted to move vertically to allow 35 the horizontal hook-bar to engage a keeper 5, arranged on the front wall, and a catch 6, arranged on the window-sill and to be disengaged from the same. The hook-bar extends transversely through the shutter and is ar- 40 ranged in slots 7 and 8 of the inner and outer plates 9 and 10, which form guides for the horizontal hook-bar, and the outer plate of which secures the slide in the vertical groove of the shutter. The outer plate 10 is provided 45 near its lower end with a horizontal extension 11, which, when the shutter is open, is adapted to engage a projection 12 of the keeper 5 to prevent the shutter being lifted off the pinnacles by a heavy wind. The keeper 5 is pro- 50 vided with a horizontal loop to receive the outer hook of the gravity-latch and the pro-

jection 12 is arranged at the outer end of the loop. The gravity-latch is lifted out of engagement with the keeper by an angle-lever 13, which is fulcrumed on the shutter, and 55 has the outer end of one arm arranged beneath the horizontal hook-bar, and the other arm is provided at its end with a handle 14, arranged near the inner end of the shutter, within easy reach, and adapted to be depressed 60 to lift the latch to enable a shutter to be closed without necessitating a person leaning far out a window. When the shutter is closed, the inner hook of the horizontal bar engages a catch or stop 6 and the inner end of the hook- 65 bar is slightly enlarged and is provided with an opening, by means of which the latch may be readily raised to open the shutter. In order to prevent the latch being raised from the outside when the shutter is closed, a button 70 15 is pivoted at the upper end of the inner plate 9 and is adapted to be turned longitudinally of the plate 9 to engage the horizontal hook-bar and prevent the latter being raised.

It will be seen that the shutter-fastener and 75 means for operating the same are simple and comparatively inexpensive in construction; that a shutter may be readily closed without necessitating a person leaning far out of the window, and that when the shutter is closed 80 it is securely locked and cannot be opened from the outside.

What I claim is—

The combination, with a shutter provided 85 with a vertical groove, of a gravity-latch mounted on the shutter and composed of a slide arranged in the groove and a horizontal bar extending through the shutter and pro- 90 vided at each end with a hook, an outer plate secured to the shutter and provided with a slot to receive the bar and having a horizontal flange, and a keeper adapted to be engaged by the hook and the flange, substantially as described.

In testimony that I claim the foregoing as 95 my own I have hereto affixed my signature in the presence of two witnesses.

MANING F. TEN EYCK.

Witnesses:
